Andrew Little of New York, N.Y.

Letters Patent No. 3,034, April 18, 1865.

Design for Letter-press type.

The schedule referred to in the Letter Patent and making part of the same.

To all whom it may concern:

Be it known that I, Andrew Little of the City, County and State of New York, have invented or produced a new and original Design for Letter-press type, which I have named or designated as the "Rimmed Shaded Roman Script," and I do hereby declare that the following is a full and exact description of the same.

The virtue of my invention consist in combining with the ordinary Roman type, letter or character, a fine, or marginal hair line, projected in perspective, so as to the letter as relief from the background, (though not in heavy shading according to the theory of lights and shadows) and thereby not only producing a new style of type, but at the same time a very pleasing effect upon the observer.

But to describe my invention more particularly I will refer to the accompanying drawings or specimens of the "rimmed shaded Roman script" forming a part of this specification the same letters of reference indicating they occur, referring to like parts.

Figure 1 represents an alphabetical view of the "Rimmed shaded Roman script."

Letter a, represents the ordinary letter or character of the Roman alphabet, having a delicate marginal outline or rim, entirely around the main or body letter, forming what may be characterized a letter within a letter. But with the peculiarity of

the outlined letter being somewhat ovate in form, and larger than the body letter, and touching nearly the upper and left hand marginal outline, or, in other words, and by so doing, projecting the lower and right hand marginal outlines, or, in other words, a considerable space beyond the body of the letter,

so as to give the appearance of a shaded letter, or a letter in relief from the background, and thereby overcome the apparent heaviness of the Roman letter or character when printed in solid mass.

It will be obvious that the beauty of the design is dependent upon its uniformity and therefore as the same peculiarity of outline is carried out in each letter or character of the "Roman Script," it will be apparent that the design will be complete or entire only when used as an entire series of "Rimmed Shaded Roman Script."

I am aware that shaded type letters have been previously used. But in all such type letters the shadows have been heavy and only projecting from the base lines of the letter.

My design therefore differs from such shaded letters in this, that the rim, or marginal outline, is only a thin or fine thread extending entirely around the sides of the main letter, thereby producing an effect peculiar to the design, and at the same time, much more pleasing to the eye, than if only a heavy shadow appeared, as projected from a heavy body, like the Roman letter.

Having now described my invention I will proceed to set forth what I claim and desire to secure by letters patent of the United States.

Claims

I claim the use of the ornamental design for printing type, designated by me as the "Rimmed shaded Roman Script," as hereinbefore set forth.
